UNITED STATES PATENT OFFICE

2,268,278

BUILDING SIDING MATERIAL

Abbott Coburn, Chicago, Ill.

Application February 21, 1941, Serial No. 380,045

13 Claims.

(Cl. 20—5)

My invention relates more particularly to building siding material of sheet or panel-like form made to simulate the appearance of shingles, as for example and more particularly, of wood, arranged, as for instance, in horizontal rows.

One of my objects is to cause the lower edges of shingle-simulating portions of the material, the outer exposed surfaces of which are disposed in a common plane, to present to an observer, the appearance of lapped shingles of substantial thickness, preferably of substantially the same thickness, throughout the surface of a wall to which the material is applied; another object is to provide a siding material panel of such construction that when a number of such panels are grouped together the structure will present the appearance of a shingle structure wherein certain of the shingles extend at their lower edges below the shingles next laterally adjacent thereto; and other objects as will be manifest from the following description.

Referring to the accompanying drawing:

Figure 1 is a face view of a grouping of similar building siding panels embodying my invention, the two upper panels being shown partly broken away and vertically spaced from the panel beneath them, shown in full, to better illustrate a certain feature of the invention.

Figure 2 is a plan or top edge view of the panel;

Figure 3, an enlarged sectional view taken at the line 3 on Fig. 1 and viewed in the direction of the arrow; and

Figure 4 is a detail face view of the top edge of the lower panel of Figure 1, showing its appearance separate from the upper panels of said figure.

I have illustrated my invention as embodied in a building siding panel which in practice would be provided of a number sufficient when grouped together to cover the portion of the building to be surfaced.

In the case of the particular panel shown it is formed of a base or board portion 4 of any suitable material, as for example insulation board such as is commonly used, impregnated with waterproofing material in accordance with common practice.

Over the entire outer surface of the panel is a coating of adhesive, such as for example asphalt, covered by a layer of grit represented at 5, pressed into the coating and adhering thereto over its entire surface. The grit 5 is further locally pressed into the coating (the coating be-

ing hot), to become covered thereby, along lines or stripes delineating the particular shingle design which the panel is to display. In the particular panel shown the shingle simulating portions represented at 6 are provided in two horizontal rows, the shingle-simulating portions being of different widths and shown as simulating wood shingles. The shingle-simulating portions of the rows thereof are staggered relative to each other and the lower ends of alternate shingle-simulating portions of each row extend below the lower edges of the shingle-simulating portions next laterally adjacent thereto.

The stripe of asphalt coating exposed between the rows of shingle-simulating portions and extending lengthwise of the panel and of zigzag form as shown in Fig. 1, is represented at 7 and the vertical stripes of the asphalt coating which separate the shingle portions of each row are represented at 8. The stripe 7 is of zigzag form to cause those portions of the stripe which extend below the shingle-simulating portions of the upper row thereof the lower edges of which are below the laterally adjacent shingle-simulating portions, to be of substantially the same width as the portions of the stripe below the other shingle-simulating portions of this row.

It is contemplated that in covering a wall surface a plurality of the panels shown be assembled together in matching relation to produce a continuous uniform design, the panels of alternate horizontal rows thereof being staggered relative to the panels of the rows immediately above and below them, as indicated of the upper panels in Fig. 1, wherein the two upper panels, portions of which are broken away, are shown as meeting midway between the ends of the panel beneath them as indicated at 9.

As the lower edges of certain of the shingle-simulating portions 6 at the lower edge of the panel, when the panel is grouped with similar panels, as shown, register with shingle-simulating portions of panels beneath it, the upper edges of which portions extend flush with the upper edge of the exposed surface of the lower panels, the panel is formed to provide stripes 10 of asphalt coating, depressed relative to the exposed surface of the panel, along the lower edges of the first above referred to shingle-simulating portions. Furthermore, the upper edge portion of the panel is formed with stripes 11, likewise depressed, of asphalt coating which, when this panel is grouped with similar panels as shown, will be in registration with such of those of the shingle-simulating portions of the panels im-

mediately above it as extend to the extreme lower edges of these last referred to panels.

Thus the stripes between any one of the panels and the panels immediately above and below it will be of the same zigzag form presenting between the lower edge of each shingle-simulating portion and the upper edge of the shingle-simulating portion beneath it, a stripe of asphalt coating of substantially the same width.

Inasmuch as at least the greater portion of the wall of a building is at a much higher elevation than the ground, a person viewing the wall and looking upwardly at it, views it at a decided angle to the horizontal and therefore in perspective. As the horizontal stripes of asphalt coating between the shingle-simulating portions of each panel and between adjacent panels (these stripes presenting the optical illusion of thick butt shingles), are inset from the exposed surface of the panel, forming depressions, such depressions if of straight sided form would present to the eye of the observer viewing the siding on the wall of a building, at an angle as stated, decidedly narrower stripe effects as compared with the relatively wide stripe effects presented to the eye of the observer viewing the surfacing substantially horizontally. Thus the optical illusion of thicker butt shingles produced by these horizontal stripes becomes successively diminished toward the top of the surfaced area producing an appearance decidedly non-uniform and therefore objectionable.

To minimize this objection the lower side wall of the horizontal stripe-forming zigzag depression 7 throughout its length and the lower side walls of the stripe-forming depressions 11 are sloped downwardly and outwardly throughout their length as represented at 12 of the central stripe-forming depression 7 and at 13 of one of the stripe-forming depressions 11 extending along the top edge of the panel.

While I have illustrated and described a particular construction embodying my invention, I do not wish to be understood as intending to limit it thereto as the same may be variously modified and altered and the invention embodied in other forms of structure without departing from the spirit thereof.

What I claim as new and desire to secure by Letters Patent is:

1. Building siding material comprising a base member presenting shingle-simulating portions spaced from each other, the surface of the material between said shingle-simulating portions being darker than said portions, said surface below certain of said shingle-simulating portions being depressed, the lower side walls of said depressions inclining outwardly and downwardly from the bases of said depressions to an overall width of depression substantially equal to the width of said darkened portions.

2. Building siding material comprising a base member presenting shingle-simulating portions spaced from each other, the surface of the material between said shingle-simulating portions being darker than said portions, said surface below said shingle-simulating portions being depressed, the lower side walls of certain of said depressions inclining outwardly and downwardly from the bases of said depressions to an overall width of depression substantially equal to the width of said darkened portions.

3. Building siding material having depressions in its exposed surface delineating shingle-simulating portions, the surfaces of said depressions

being darker than said portions, the lower side walls of said depressions beneath certain of said portions inclining outwardly and downwardly from the bases of said depressions to an overall width of depression substantially equal to the width of said darkened portions.

4. Building siding material comprising a base member presenting substantially horizontally disposed rows of shingle-simulating portions spaced from each other, the surface of the material between said shingle-simulating material being darker than said portions, said surface below certain of said shingle-simulating portions being depressed, the lower side walls of said depressions inclining outwardly and downwardly from the bases of said depressions to an overall width of depression substantially equal to the width of said darkened portions.

5. Building siding material comprising a base member presenting substantially horizontally disposed rows of shingle-simulating portions spaced from each other, the surface of the material between said shingle-simulating material being darker than said portions, said surface below said shingle-simulating portions being depressed in zigzag relation in alternate depressions, the lower side walls of certain of said depressions inclining outwardly and downwardly from the bases of said depressions.

6. A building siding panel presenting shingle-simulating portions spaced from each other, an edge of the exposed surface of said panel at a portion only of said edge having a stripe for registration with a plain end of a shingle-simulating portion of a panel assembled with said first-referred-to panel.

7. A building siding panel presenting shingle-simulating portions spaced from each other, an edge of the exposed surface of said panel having spaced apart stripes for registration with plain ends of spaced apart shingle-simulating portions of a panel assembled with said first-referred-to panel.

8. A building siding panel presenting shingle-simulating portions spaced from each other, an edge of the exposed surface of said panel having spaced apart stripes for registration with ends of spaced apart shingle-simulating portions of end to end disposed panels assembled with said first-referred-to panel in staggered relation thereto.

9. A building siding panel presenting shingle-simulating portions spaced from each other, certain of said portions extending to an edge of the exposed surface of the panel, said edge at a portion thereof in registration with one of said shingle-simulating portions reaching short of said edge, having a stripe for registration with an end of a shingle-simulating portion of a panel assembled with said first-referred-to panel, reaching to an edge of said last-referred-to panel.

10. Building siding comprising, in combination, an assembly of panels having shingle-simulating portions spaced from each other, an edge of the exposed surface of one of said panels at the joint between said panels, at a portion only of said edge, having a stripe which registers with an end of one of the shingle-simulating portions of the other of said panels.

11. Building siding comprising, in combination, an assembly of panels having shingle-simulating portions spaced from each other, an edge of the exposed surface of one of said panels at the joint between said panels having stripes spaced apart along said edge which register with

ends of certain of said shingle-simulating portions of the other of said panels.

12. Building siding comprising, in combination, an assembly of panels in staggered relation and having shingle-simulating portions spaced from each other, the edge of the exposed surface of one of said panels at the joints between it and the others of said panels having stripes spaced apart along said edge which register with ends of certain of said shingle-simulating portions of said 10 other panels.

13. Building siding comprising, in combination, an assembly of rectangular panels having straight edges and presenting shingle-simulating portions spaced from each other, one edge of the exposed surface of one of said panels at the joint between said panels, at a portion only of said edge, having a stripe which registers with an end of one of the shingle-simulating portions of the other of said panels.

ABBOTT COBURN.
